PRINTING MACHINE

Irving Gurwick, Harmon, N. Y., assignor to Shell-mar Products Company, Chicago, Ill., a corporation of Delaware

Application July 31, 1933, Serial No. 682,923

15 Claims. (Cl. 101—152)

The present invention relates to the printing art, and has particular reference to an improved printing method and a machine of the intaglio type which have been found of great advantage 5 in the printing of such materials as transparent cellulose sheeting.

A principal object of the invention is the provision of a multi-color intaglio press for printing transparent cellulose sheeting.

10 An additional object is to provide an intaglio press which is easily operated to produce printing of high quality.

A further object is the provision of an intaglio press which is particularly flexible and easily 15 adjusted.

A still further object is the provision of an improved method of intaglio printing.

These and other objects will be evident from 20 a consideration of the following illustrative and explanatory description, and by reference to the accompanying drawings, in which

Fig. 1 is a side view of a press constructed in accordance with my invention;

Fig. 2 is a side view of the first printing unit 25 of the press;

Fig. 3 is an end view of the unit shown in Fig. 2;

Fig. 4 is a sectional view taken along line 4—4 30 of Fig. 1 and discloses an end view of an intermediate color unit;

Fig. 5 is a top view of the unit shown in Fig. 4; and

Fig. 6 is a side view of the driving mechanism 35 for the cutting unit of the machine.

As shown in the drawings, the press is formed of a plurality of longitudinally movable units 40 mounted in series upon a suitable base and having cooperating feed and disposal units. Each 45 unit is complete in itself and operable to print a single color.

The base of the printing machine is composed of two longitudinally-extending frames 10 and 11 which may be mounted on a common support for stability. In the exterior of frames 10 and 11 respectively are mounted longitudinal rack members 12 and 13. As will be observed in Fig. 1, both the base frames 10 and 11 and the rack bars 12 and 13 which are secured thereto extend substantially the entire length of the printing 50 machine.

At one end of the press is a feed unit having side frames 14 and 15 respectively mounted on base frames 10 and 11. Frame unit 14 is provided with an idler gear 16 which meshes with 55 rack bar 12 on one side and with a second gear

17 on its opposite side. Gear 17 is carried on a rotatable shaft 18 extending upwardly and being connected with a beveled gear 19. Meshing with the latter gear is a similar beveled gear 20 which is keyed to a shaft 21. The shaft 21 extends transversely of the printing machine and is journaled in frame units 14 and 15.

Adjacent the opposite end of shaft 21 is a beveled gear 22 which meshes with a second beveled gear 23 mounted on a vertical rotatable 10 shaft 24. Shaft 24 also has keyed to it a gear 25 which meshes with an idler gear 26, the latter being engaged on its opposite side with rack bar 13.

To one end of shaft 21 is keyed a hand wheel 15 27, and it will be seen that by operation of this hand wheel the position of the feed unit 25 may be changed as desired. That is, rotation of the hand wheel to the right, for example, will transmit motion through shaft 20 and 20 finally to idler gears 17 and 26, causing these idler gears to travel along the rack bars away from the first printing unit.

Mounted in frame units 14 and 15 are two shafts 28 and 29 which are respectively adapted 25 to carry rolls 30 and 31 of transparent cellulose sheeting or other web material. Suitable changing mechanism and brakes 32 are provided on the ends of shafts 28 and 29, whereby the shafts may be removed easily for changing rolls and 30 the tension of the web may be properly controlled. Ordinarily, only one roll of the material will be used for the printing operation, and the other roll will be attached to the end of the web when the roll previously in use is exhausted. 35

Adjacent the upper portion of frames 14 and 15 are mounted transverse steel guide rollers 33, 34, 35 and 36. These rollers are mounted in spaced relation and in fixed position in the frame units. Between rollers 33 and 34 is a rubber 40 surfaced roller 37 and between rollers 34 and 35 is a similar rubber surfaced roller 38. The ends of rollers 37 and 38 are rotatably mounted in end frames 39, which are mounted in suitable slides 40 in the frames 14 and 15. Through the 45 center of each of frames 39 is threaded a shaft 41. These shafts are rotatably mounted in frames 14 and 15 respectively and have beveled gears 42 on their outer ends. Beveled gears 43, 50 meshing with gears 42, are keyed to a transverse shaft 44 which is suitably journaled in frame structures 14 and 15. A hand wheel 45 is keyed to one end of shaft 44, and by rotation of this hand wheel, the relative position of the rubber 55

faced rollers 38 and 39 with respect to the fixed rollers 33, 34 and 35 may be changed as desired.

Between rollers 35 and 36 a third adjustable rubber faced roller 46 is mounted in blocks 47, the latter being positioned in suitable slides 48 in the frame units 14 and 15. A shaft 49 is threaded in each of the blocks 47, and beveled gears 50 are keyed to the outer end of these shafts. Similar beveled gears 51 mesh with gears 50 and are keyed to a transverse shaft 52 which is journaled on frame units 14 and 15. A hand wheel 53 is secured to one end of shaft 52 and by operation of this wheel the position of the rubber faced roller 46 may be adjusted as desired.

As shown in Fig. 2, the web of cellulose sheeting is passed from roll 39 about guide rolls 54, 55 and 56, and then through the system of steel and rubber rolls described heretofore. More particularly, the web is passed between the rubber faced rolls 37, 38 and 46. By properly adjusting the relative position of the rubber rolls with respect to the steel rolls, by means of hand wheels 45 and 50, the desired web control may be obtained. When the web is taken from roll 31, the guide rolls 54 and 55 are not used.

From the feed unit the web passes to the first color unit. Each of the color units is of substantially the same construction, and the description of one will be sufficient for a complete understanding of all the units.

Upon base frame 10 is mounted a vertical printing frame 57 and a similar frame 58 is positioned on base frame 11. The color units are provided with arrangements for adjusting their longitudinal position on the base frame which are substantial duplicates of the mechanism for adjusting the longitudinal position of the feed unit, and the reference numerals and description of the mechanism for adjusting the position of the feed units may be taken as applicable to the color units. That is, frame 57 is provided with a gear 16 meshing with rack bar 12, a gear 17 meshing with gear 16 and carried on a vertical shaft 18, and a beveled gear 19 on the top of shaft 18 meshing with a similar gear 20 which is keyed to shaft 21. On the opposite side of the machine, frame 58 carries a gear 26 meshing with rack bar 13 on one side and with gear 25 on the other side, the latter gear being keyed to vertical shaft 24 which is provided with a beveled gear 23 on its top meshing with a similar gear 22 on shaft 21. By operation of hand wheel 27 it is possible to regulate the position of the color units as explained heretofore with respect to the feed unit.

Above the position regulating mechanism for the color unit is a cross frame member 59 which joins the side frame units 57 and 58. As will be seen in Fig. 5, the cross frame 59 carries two auxiliary frame units 60 and 61 which are slidably mounted so as to be adjustable transversely of the printing machine. Each of these auxiliary frame units carries a bearing in which is mounted the shaft 62 of an intaglio printing cylinder 63. The auxiliary frame member 61 has an opening into which is threaded a shaft 64, the latter being rotatably mounted in the frame structure 59 and provided with a hand wheel 65. By operation of the hand wheel 65, it is possible to adjust the transverse position of the printing cylinder. In printing a plurality of colors, transverse adjustment of the various printing cylinders is important in order to insure proper registration of prints.

To the end of shaft 62 opposite the hand wheel 65 is secured a split or slotted portion 66 which receives tongue 67 of a short shaft 68. Shaft 68 enters gear box 69 and has on its end a beveled gear 70 which meshes with a similar gear 71 keyed to vertical shaft 72. Shaft 72 extends downwardly and is connected to a beveled gear 73 which meshes with a similar gear 74 carried on a main drive shaft 75. Gears 73 and 74 are mounted in such a manner as to move along shaft 75 when the longitudinal position of the printing unit is changed. The main drive shaft 75, which may be driven by any suitable means such as a belt and pulley shown at 76, is square to permit the beveled gears 74 to move to any desired position. Instead of the belt and pulley drive shown in Fig. 1, I have found it particularly desirable to employ an oil gear drive for the shaft 75. The operation of the printing machine is quite simple since the etched printing cylinder is the only element driven directly from the main source of power.

The etched printing cylinder 63 rotates in a bath of a suitable quick-drying ink such as a lacquer ink held in a tank 77 which is slidably mounted on the frame structure 59 so as to be transversely adjustable. That is, rotation of hand wheel 65 causes the etched printing cylinder to move transversely of the printing machine, and the tank 77 follows this movement.

Mounted adjacent the etched printing cylinder is a doctor mechanism which operates to remove excess ink from the printing cylinder prior to its contact with the cellulose web. This doctor mechanism includes a rigid holder 78 having blocks 79 which hold opposite ends of a flexible doctor blade. The doctor blade holder 78 is removably mounted on a support plate 80 by means of hand clamps 81 which may be rotated into clamping position with respect to the doctor blade holder. The support plate 80 is adjustably positioned on a bar 82 and this bar is rotatably mounted in vertically adjustable journals 83. To provide for vertical adjustment the journals 83 have threaded through them the vertical shafts 84. These shafts extend downwardly and have beveled gears 85 on their lower end meshing with similar gears 86 keyed to shaft 87. Intermediate the ends of shaft 87 is secured a bevel gear 88 with which is meshed a similar beveled gear 89, the latter being keyed to a shaft 90 having fixed to its outer end a hand wheel 91. It will be seen that by rotation of this hand wheel the fixed shaft 84 which is threaded into journals 83 is caused to turn, thereby raising or lowering the doctor blade.

In addition to this vertical adjustment, it is possible to rotate the doctor mechanism about shaft 82 in order to obtain access to the color bath and printing cylinder. The vertical adjustment is important from the standpoint of obtaining the proper angle of contact of the doctor blade with the printing cylinder, as in the case of a change in size of the printing cylinder. Also, in some cases it will be desirable to pass the web directly and on a horizontal line from one printing unit to the next adjacent unit rather than as described hereinafter, and for this reason it is desirable to be able to lower the doctor mechanism before rotating the same to gain access to the color bath. Otherwise, rotation of the doctor mechanism will cause a break in the cellulose web. When the doctor mechanism is lowered for this purpose, it is generally desired later to return it to its original adjust-

ment. For this purpose I have provided frames 92 having mounted therein rotatable shafts 93 which are threaded into stops 94, the latter being held against rotation by engagement with slots 95 in frames 92, and will be observed in Fig. 4. When the proper vertical adjustment of the doctor mechanism is obtained, hand wheels 96 are rotated until stops 94 are brought down into contact with cooperating stops on the journals 83. Subsequent lowering of the doctor mechanism does not necessitate readjustment for vertical position, since it is required merely to raise the doctor mechanism by means of hand wheel 91 until the journals 83 engage stops 94, thereby again positioning the doctor mechanism.

Positioned above the printing cylinder is an adjustable impression cylinder unit which may be pivoted out of its normal operating position to allow access to the printing cylinder. This unit includes a side frame 97 pivoted adjacent one side of frame 59 and a similar frame 98 pivoted adjacent the opposite side of frame 59. Side frames 97 and 98 are each carried on a transverse shaft 99 the ends of which are journaled in opposite sides of the frame 59. Shaft 99 also carries swing arms 100 which are provided with arcuate rack bars 101. The teeth of these arcuate rack bars mesh with worms 102 carried on vertical shafts 103 the lower ends of which are provided with beveled gears 104. Gears 104 mesh with beveled gears 105 keyed to the outwardly extending transverse shaft 106. To the end of shaft 106 is keyed a hand wheel 107. By rotating this hand wheel the impression cylinder unit is caused to rotate about shaft 99, its inoperative position being shown in dotted lines in Fig. 2, thereby permitting the etched printing cylinders to be removed without hindrance.

The impression unit frames 97 and 98 are respectively provided with vertical slide portions 108 and 109. Slidably mounted in these portions of the frame structures are impression cylinder frames 110 and 111. A rotatable shaft 112 extends between frame units 97 and 98 adjacent their tops. This shaft carries a beveled gear 113 on one end which meshes with a similar gear 114 keyed to a vertical shaft 115. The lower end of shaft 115 is threaded into the frame structure 110. Adjacent the opposite end of shaft 112 is mounted a beveled gear 116 which meshes with a similar gear 117 on vertical shaft 118, the lower end of the latter being threaded into the frame structure 111. It will be seen that by rotation of hand wheel 119, which is keyed to the end of shaft 112, the frame structures 110 and 111 are caused to move at the same time forward or away from the etched printing cylinder. The purpose of this adjustment is to provide means for raising and lowering the rubber surfaced impression roll 120 into and out of contact with the printing cylinder, it being understood that the web of cellulose material passes between the impression roll and printing cylinder. The impression roll has its ends journaled in swing arm frames 121 and 122 which are pivoted to a shaft 123 extending between frame structures 110 and 111. Immediately in front of the rubber impression roll is a steel guide roll 124 which is also journaled in frame portions 121 and 122. The cellulose web passes beneath this steel roll before it contacts with the printing cylinder in order that the web may be given a substantially horizontal plane

of travel as it contacts the printing cylinder. Preferably, the guide roll 124 is slightly higher than the impression roll, as shown in Fig. 2, whereby the web has a slight downward slant toward the printing cylinder. This reduces the amount of contact of the web with the printing cylinder and thereby reduces the chances of the web being smeared by the printing cylinder, and permits sharper outlines to be obtained in the printed image. The swing arms 121 and 122 are pivoted about shaft 123. The forward ends of the swing arms are supported by bolts 125 extending through bars 126 and being threaded into the shaft upon which roll 124 is mounted, the bars 126 being secured to frames 110 and 111. By turning bolts 125 the forward end of the swing arms may be raised or lowered.

Above the rubber impression cylinder 120 is mounted a vertically adjustable steel pressure cylinder 127. This cylinder is journaled in blocks 128 and 129 which are slidably mounted in frame structures 110 and 111 respectively. A shaft 130 extends downwardly through frame structure 110 and is threaded into block 128. The end of the steel roll 127 may be raised or lowered by adjustment of pin 131 which extends through the upper portion of shaft 130. Roll 127 presses against the rubber impression roll and by properly raising or lowering the roll 127, the pressure of the impression roll against the printing roll may be suitably adjusted and distributed to obtain proper printing results. It will be understood that a shaft 132, having pin 133 in its upper end, extends through frame 111 and is threaded into block 129 which carries the opposite end of the impression roll, whereby the pressure of steel roll 127 against the rubber impression roll may be adjusted at both ends.

The shaft 123 carries short swing arms 135 in the opposite ends of which are mounted an electrically heated roller 136 of any suitable design. It will be noted that the roller 136 is closely adjacent the printing cylinder, whereby the cellulose sheeting may be subjected to a drying heat immediately after it is printed. This requires that the diameter of the heating roll be small, since otherwise it would be impractical to place the heating roll close to the printing cylinder.

The inks ordinarily used for printing cellulose sheeting are generally of the quick-drying type and contain a lacquer base. Ordinarily the solvents will be mixed and their boiling points will vary considerably. If the heat is applied at an appreciable interval after the printing operation, the high boiling solvents will have largely evaporated and the boiling point of the solvents to which the heat is applied is correspondingly higher, thereby reducing the drying efficiency. By placing the heating roll close to the printing unit, the heat is applied while the high boiling solvents are still present and consequently the boiling point of the mixture is lower. I have found that this procedure is more effective from the standpoint of drying and that the finish of the dried ink is more satisfactory. Further, unaided evaporation of the high boiling solvents causes the temperature of the printed web to be reduced considerably, and this results in the formation of a "blush" which usually indicates precipitation of cellulose hydrate. The application of heat immediately after the printing operation is also desirable from other standpoints. The quick application of heat causes the cellulose web to dry before serious trouble can happen.

in the case of badly balanced solvents. An additional advantage of this type of heating roller is that the area of contact between the heating roll and the cellulose web is low, and in many cases will theoretically be along a line of contact. The time of heating, therefore, is short and the possibility of damage to the ink or the cellulose material is reduced.

By pivoting the heating roller on swing arms, the roller may be rotated upwardly out of contact with the cellulose web as soon as the press has stopped. If the hot roll stays in contact with the web, the latter is apt to be burned or otherwise damaged. The heating roll may be constructed by enclosing stationary or rotatable resistance units with a rotatable copper or other metallic sleeve, for example.

Immediately following the drying roll is a curved bank of idler rolls 137 supported by frame units 138. The frame units 138 are pivotally mounted to the frame structure 59 as shown at 139, whereby the bank of idler rolls 137 may be rotated together. The first roll 137 of the series is close to the drying roll and the remaining rolls 25 of the bank are closely spaced together so that the cellulose web makes contact with the rolls along a plurality of closely spaced lines. By employing an arcuate bank of idlers, contact of the web with the rolls is more positive than in 30 the case of a straight bank of idlers. In practice, I have found it desirable to position the idlers at distances apart which may be of the order of 5 or 6 inches.

Adjacent the first intermediate color unit and all others thereafter are mounted upright bars 140 which extend upwardly and carry rollers 141, the latter being engaged beneath side flanges in the frames 138, thereby supporting the forward end of the bank of idlers. When the 40 units are moved longitudinally with respect to each other the rollers 141 provide means for adjusting the position of the banks of rollers, since the side flanges travel along the rollers.

The intermediate color units, as will be seen in Fig. 1, are provided with additional idler rolls 45 142 and 143 which receive the cellulose web from idlers 137 and direct it beneath the idler 123 which is positioned adjacent the impression cylinder.

50 When a web is passed through the series of color units, it is necessary to position the color units so as to obtain the best printing results. For example, the web often gets out of register. That is, the color and portion of the image printed by one unit gets out of proper position with respect to the other colors. Various registration means may be provided in a manner known to the art. For instance, a differential device may be connected through the driving mechanism for the printing cylinders. However, I have found that suitable registration may be obtained by regulation of the bank of idlers 137. Further, the color units may be moved longitudinally to change the web distance between the units, whereby to bring the units back into registration. As the units are moved longitudinally the banks of idlers are preferably rotated about their pivotal points, being retained in engagement with rollers 141.

70 In some cases it will be unnecessary to move the last color unit of the series, and for this reason no mechanism for this purpose has been shown in Fig. 1. It is obvious that such mechanism could be supplied if desired in the manner

described in connection with the other color units.

After the last color is printed, the web is directed to a suitable cutting or sheeting mechanism or to a rewinder such as shown in Fig. 1. 5 This rewinder includes side frames 144 having upright posts or bars 145 which support a plurality of idlers 146 about which the web is passed. Auxiliary frame members 147 are pivoted to the frames 144 at 148. Arcuate rack bars 149 are 10 mounted on frames 144 and mesh with worms 150. These worms are carried on short shafts 151 having beveled gears on their ends meshing with similar gears on shaft 152. By operation of hand wheel 153 the entire frame units 147 are 15 rotated about pivotal points 160. This rotation permits adjustment of the position of drive roll 154 with respect to idler roll 155, which contacts therewith. Rolls 154 and 155 exert a pressure upon the cellulose web and provide means for 20 drawing the web through the machine.

The draw roll 154 is driven by means of a shaft 156 which takes power from the worm drive shaft by means of suitable bevel gears. Drive shaft 156 has a helical or spiral gear 157 on its 25 upper end which meshes with a similar gear 158 on shaft 160. Shaft 160 also carries a gear 161 and this gear drives a change gear 162 mounted on an adjustable arm 163. The change gear drives gear 164 which is keyed to the shaft of 30 draw roll 154. The diameter of the draw roll 154 is a multiple of the diameter of the printing cylinders, and suitable change gears 162 are provided so that the peripheral speed of the draw roll is the same as the peripheral speed of the print- 35 ing cylinders. In this manner, the draw roll may be utilized for progressing the web through the machine and the pressure of the printing cylinders upon the web may be made as light as desired.

40 The printed web passes from the draw rolls 154 and 155 to a rewinding roll 165 carried on shaft 166, the latter being driven in the usual manner, as by a suitable oil gear arrangement.

It will be observed from the foregoing description that my improved press is highly flexible. The various units are adjustable as units and with respect to the other units of the machine. In operation, the cellulose web is threaded from roll 30 or 31 through the various guide 50 rolls and into the first color unit. After obtaining the first color, the web passes along a bank of idlers making frequent contact with the web for a sufficient distance to permit the freshly deposited ink to dry or set. Thereafter, 55 the web passes downwardly around the guide rolls of the second printing unit and between the second color depositing rolls. It is preferred to print a light colored opaque background in the first printing unit and deposit the subsequent 60 colors in a superimposition with respect to the base color. Suitable blowing devices may be mounted adjacent the banks of idlers to assist in drying the web by means of an air blast.

The web continues through each of the color 65 units in the manner described, and is finally received by the rewinding mechanism. As shown in the drawings, the printing machine is provided with closely spaced rolls for contacting the web along its entire length of travel. The 70 closely spaced banks of idlers make frequent contact with the web between the different color units and the guide rolls which receive the web from the banks of idlers are likewise closely spaced.

5 I have found that this frequent contact of the web with the idlers along its path of travel permits the web to be directly rewound without necessitating the use of special rewinding mechanisms having transverse adjusting means.

Where the web is permitted to travel a substantial distance without support, the web gains a weaving motion which results in relative transverse motion. A rewound web of this type will 10 have irregular edges which make it necessary to again rewind the web in special machinery which have compensating devices designed to straighten the web out. This objection may be remedied by providing for frequent contact of the web 15 with suitable guide rolls.

Three color units have been shown in Fig. 1, but it will be understood that any suitable number of the units may be employed. For instance, I have found it desirable to use five color units. 20 Also, in many cases it will be of advantage to cut the printed web into sheets rather than rewinding the web into roll form, and for the purpose of cutting the web into sheets the apparatus shown in my copending application, 25 Serial No. 492,439, filed October 31, 1930, may be utilized.

Various modifications of the structure described herein are possible without departing from the teachings of my invention, and all such 30 variations and modifications are intended to be included in the appended claims.

I claim:

1. In an intaglio printing machine for printing on transparent cellulose sheeting, means for feeding a web of said transparent cellulose sheeting, a printing unit receiving said web and including an etched printing cylinder and color bath therefor, a relatively small heating roll positioned adjacent said printing cylinder, and 40 means for moving said heating roll into and out of contact with a web passing through the machine.

2. In a printing machine, a longitudinally extending base frame, a plurality of color units 45 mounted on said base frame, a rack bar on said frame, gears rotatably mounted on said color units and engaging said rack bar, and means for rotating said gears to move said units longitudinally of said frame.

3. In an intaglio printing machine, a color 50 unit, means for progressing a web through said unit, means for rewinding the printed web, and closely spaced rolls positioned in contact with said web throughout its travel through the machine for preventing wearing of said web.

4. In an intaglio printing machine, a longitudinally extending frame, a plurality of printing units mounted on said frame, means for moving at least one of said printing units longitudinally of said frame, a curved bank of idler rolls pivotally mounted adjacent said units for engagement with a web passing through said machine, means for adjusting the position of said bank of idlers, and means adjacent the next 60 succeeding color unit for supporting the end of said bank of idlers.

5. In an intaglio printing machine, a printing unit, a bank of idlers pivotally attached adjacent said printing unit for engagement with a web passing through said machine, and means for adjusting the position of said idlers.

6. In an intaglio printing machine, a printing unit, a draw roll for pulling a web through said unit, a second roll adjacent said draw roll, pivotally mounted frame members for said draw

roll, driving means for said draw roll, and means for rotating said frame members about their pivot to vary the relative positions of said draw roll and said second roll thereby to control the tension on a web engaged between said rolls. 5

7. In an intaglio printing machine, longitudinally extending base frames, rack bars on said frames, a feed unit mounted on said frames, printing units mounted on said frame, a rewinding unit mounted on said frame, gears rotatably 10 mounted on certain of said units meshing with said rack bars, means for rotating said gears to produce longitudinal movement of said units, curved banks of rolls pivotally mounted adjacent said printing units for engagement with a 15 web passing through said machine, means for adjusting the position of said banks of rolls, and means adjacent the next succeeding printing unit for supporting the free end of each of said bank of rolls. 20

8. In an intaglio printing machine for multi-color printing of cellulose sheeting, longitudinally extending base frames, rack bars along said frames, a feed unit mounted on said frames, rotatable gears on said feed unit meshing with 25 said rack bar, means for rotating said gears for adjusting the longitudinal position of said feed unit on said frames, a plurality of printing units mounted on said frames, means for transverse adjustment of said printing units, heating rolls 30 adjacent said printing units, rotatable gears on certain of said printing units meshing with said rack bars, means for rotating said gears for adjusting the longitudinal position of said printing units, a rewinding roll, and relatively closely 35 spaced idler rolls between said feed unit and said rewind roll for contacting a web along a plurality of transverse closely spaced lines.

9. A method of printing cellulose sheeting, which comprises maintaining a traveling web of 40 said sheeting, depositing coloring material on said traveling web, winding the colored web into roll form, and supporting said traveling web throughout its path of travel along transverse lines sufficiently closely spaced to maintain said 45 web in transverse alignment.

10. In a machine for handling a web of transparent cellulose sheeting, means for supporting a roll of the sheeting, means spaced a substantial distance from the supporting means for 50 drawing a web from said roll, and a plurality of closely spaced transverse idlers between the supporting means and the drawing means, said idlers engaging said web along transverse lines spaced apart a sufficiently small distance to 55 maintain the web in transverse alignment.

11. In an intaglio printing machine, a frame structure, a feed unit, a plurality of spaced color units, and adjustable bank of relatively closely spaced idlers between said color units, and means 60 for producing relative longitudinal movement between said units.

12. In an intaglio printing unit, a frame structure having a printing cylinder support positioned for upward removal thereof, a printing 65 cylinder releasably positioned in the support of said frame structure, a color bath positioned beneath said cylinder, an auxiliary frame structure pivotally mounted on said first named frame structure, an impression cylinder mounted 70 in said auxiliary frame structure and adapted to cooperate with said printing cylinder for the printing of a web passed therebetween, means for rotating said auxiliary frame structure sufficiently to allow removal of said printing cylinder. 75

der, and additional means for adjusting the relative position of the impression cylinder with respect to the printing cylinder.

13. In an intaglio printing machine, a printing unit including an etched printing cylinder, color bath, and doctor blade mechanism rotatable into and out of contact with said printing cylinder, adjusting means for fixing the position of the doctor blade with respect to the printing cylinder, means for moving the doctor mechanism upwardly into printing position and downwardly out of printing position, and stop means for limiting the upward movement of said doctor mechanism.
14. In an intaglio printing machine, means for supporting a roll of material to be printed, a draw roll for progressing said material through the machine, a color unit between said supporting means and said draw roll, and additional

rolls positioned along the entire path of travel of said material between said supporting means and said draw roll, said additional rolls engaging said material and being sufficiently closely spaced to maintain said material in transverse alignment. 5

15. In an intaglio printing machine, a support for a roll of material to be printed, a draw roll for progressing said material through said machine, a plurality of consecutive printing units 10 positioned between said support and said draw roll, and additional rolls positioned along the entire path of travel of said material between said printing units, said additional rolls engaging said material and being sufficiently closely 15 spaced to maintain said material in transverse alignment between said units.

IRVING GURWICK.
